UNITED STATES PATENT OFFICE.

D. F. LUSE AND A. P. LUSE, OF SPRING MILLS, PENNSYLVANIA.

IMPROVEMENT IN STUMP-EXTRACTORS.

Specification forming part of Letters Patent No. 35,827, dated July 8, 1862.

To all whom it may concern:

Be it known that we, D. F. LUSE and A. P. LUSE, of Spring Mills, in the county of Centre and State of Pennsylvania, have invented certain new and useful Improvements in Stump-Extractors; and we do hereby declare that the following is a description of the same in terms which we now think sufficiently full, clear, and exact, reference being had to the annexed drawings, making a part of this specification, in which—

Figure 1 is a side elevation, and Fig. 2 an end elevation.

The nature of our invention consists in so attaching the lever to the elevating-racks that each rack shall act alternately as the fulcrum of said lever, while both are allowed a certain degree of deviation from a vertical line to accommodate them to the varying line of draft.

It also consists in the peculiar construction and operation of the pawls or dogs.

To enable others skilled in the art to make and use our invention, we will proceed to describe its construction and operation.

The block A, rounded on its under side, as seen at b, is supported by the plates B B' of the frame-work C, which are scored for a bed for the said block, as represented at a. The uprights of this frame are braced by the bars c c', which are hinged so as to admit of removal, for the admission of the stump within the frame, when it is dragged over it by the team attached to the staples d or d' in the runner-formed sills D D'. The block A is mortised through vertically at its center and between the plates B B', the said mortise being beveled outwardly and downwardly, as represented by the dotted lines e e. A metallic plate, E, provided with two rectangular openings, covers this mortise, and within the mortise and rectangular openings are received the racks F F', provided with holes g, instead of the usual teeth. To the lower ends of these racks is suspended the double-acting lever G, by means of the yoke H, the said racks being pivoted or hinged to the said yoke, as seen at h h', and the clevis f, to which the chain I is attached, pivoted between them at the exact center of the lever G. The pawls or dogs engaging with the racks F F' are constructed as follows: A segment of a circle, i, provided with a series of holes, rises from a forked piece, j, which is pivoted or hinged to the

ears k k'. This segment at the crotch of the fork rests upon the pin l, which slides between the ears k k' and the pins m m. A rod, n, connects the segment i with the pin and communicates to it a longitudinal motion lengthwise of the block A. The pawl or dog on the left of the rack F is constructed in the same manner, and need not be further described.

The operation of our machine is as follows: The chain I being fixed to the stump, one operator takes hold of or the team is attached to the rope J, when that end of the lever G is depressed, the rack F acting as the fulcrum, and the rack F' gradually elevated. At the same time the inner end of the pin l and segment i are elevated and the former gradually withdrawn from its hole g until it drops down upon the block, where the weight of the segment i forces it into the next succeeding hole, where the rack F' is held and acts as the fulcrum in its turn during the depression of the opposite end of the lever G. The leverage exerted upon the pin l may be modified by changing the rod n from hole to hole in the segment i. When it is desired to release the racks F F', they may be slightly elevated by the lever G, which will allow of the easy-withdrawal of the pin l by means of the cord K.

By means of the rounded block A and beveled mortises e e the racks F F' are permitted to swing either to the right or left, or hither or thither, whereby the said racks may always be kept in a direct line with the line of draft, however much that may vary.

Having thus described our invention and pointed out the manner in which it operates, what we claim therein as new, and desire to secure by Letters Patent, is—

1. The combination of the lever G with the racks F F', when each of the said racks acts alternately as the fulcrum of the said lever and when both are allowed to change their line of draft by means of the rounded block A and beveled mortises e e, substantially as described.

2. The combination of the segment i, pin l, and rod n, as and for the purpose specified.

D. F. LUSE.
A. P. LUSE.
